CLAIM

The ornamental design for an oven door, as shown and described.

DESCRIPTION

FIG. 1 is a front perspective view of an oven door showing our new design;

FIG. 2 is a front view thereof;

FIG. 3 is a right side view thereof;

FIG. 4 is a left side view thereof;

FIG. 5 is a top view thereof;

FIG. 6 is a front perspective view of an alternative embodiment of the oven door showing our new design;

FIG. 7 is a front view thereof;

FIG. 8 is a right side view thereof;

FIG. 9 is a left side view thereof; and,

FIG. 10 is a top view thereof.

The broken lines depicting the handles and the remainder of the oven door represent features which form no part of the claimed design.

1 Claim, 8 Drawing Sheets
